United States Patent Office.

N. A. GRAY, OF CLEVELAND, OHIO

Letters Patent No. 77,031, dated April 21, 1868.

IMPROVEMENT IN STEAM-PLoughs.

The Schedule referred to in these Letters Patent and making part of the same.

TO ALL WHOM IT MAY CONCERN:

Be it known that I, N. A. GRAY, of Cleveland, in the county of Cuyahoga, and State of Ohio, have invented certain new and useful Improvements in Steam-Ploughs; and I do hereby declare that the following is a full and complete description of the construction and operation of the same, reference being had to the accompanying drawings, making part of this specification, in which—

Figure 1 is a side view of the plough.

Figure 2, a view of the top.

Figures 3 and 4 are detached gangs of spades or cutters.

Figures 5 and 6, detached sections, to which reference will be made.

Like letters refer to like parts in the different views.

The nature of my invention relates to the structure and adjustment of the spades, blades, or cutters, and the mode of operating them to the construction of the compound crank.

Another improvement relates to the manner of attaching the spades and picks to the handles, and is an improvement on a former machine for which Letters Patent were granted me, October 27, 1863.

A, fig. 1, represents the propelling-power or engine-boiler, driving-wheels, or gear, to the rear of which the gang of spades and picks B are attached and operated, all of which blades are the same in general construction and arrangement.

The manner described of attaching the gang of spades and picks with the crank and bearing-wheels N differs from the former plough, which was done in a fixed and rigid manner, so that, in uneven ground, the gang was depressed or elevated as by the lowering or raising of the rear end of the machine. To avoid this, the joint or hinge at F was constructed, so as to allow the gang to adjust itself independently of the main machine, and whereby the compound crank and gang can be elevated at pleasure independently of the main machine by means of the crank E and chain D, fig. 1.

This raising and lowering or adaptability of the gang does not in the least interfere with the gearing by which they are operated by steam from cylinder O, connecting-rods P P, steam-crank Q, and endless chains G G, which, combined, drive the gang B, fig. 1.

The pitch of the spades may be made more or less vertical by moving the upper end of the spade-arms J, fig. 1, back or forward by means of the slots I and rod H, fig. 2. J, fig. 6, shows the head of the handle provided with tenons k k, which are closely fitted to and inserted in mortises cut in the cross-piece K. The tenons a a, at the upper end of the spade M and pick L, fall into a mortise in the head J, above the tenon k, and are fastened and held there by keys R, as shown in fig. 5.

In my former ploughs the spade-handles were horizontal, and a permanent stud formed half the journal, and the pick the other half, and also the crank S, fig. 2, was so constructed as to cause the spades to strike consecutively on the succeeding pair adjacent, as shown in fig. 4, where they follow as the numbers 1, 2, 3, 4, &c.

By this arrangement, spades could be lengthened or widened, but not both without colliding with others. In the improved machine, spades will be carried as in fig. 5, which will admit of greater length and width without collision, and the pairs will strike as the order of odd numbers, 1, 3, 5, 7, &c., followed by the even numbers 2, 4, 6, 8, &c., fig. 5, and the machine may be made to operate any number of spades and picks in gang.

The tendency of the gang being to propel the main machine, I have attached the cog-wheel T, which works in a pinion on the main power-crank Q, by cogs on its outer disk, and by pinion U in pins on the ground-wheel V, in such manner as to adjust the velocity of the machine to the revolutions of the compound crank which carries the gang, so that it can go no faster than it digs, and dig no faster than it goes.

The mode of turning or steering the machine is by an upright shaft, with pinions at the top and bottom meshing into cogs on a section of a circle, as shown at W, fig. 2.

What I claim as my improvement, and desire to secure by Letters Patent, is—

1. So hanging or jointing the digging-apparatus to the locomotive that the said apparatus will have an

independent adjustment, whereby it is rendered adjustable according to the unevenness of the ground, in the manner and by the means substantially as set forth.

2. The stay I, rod H, and arm J, arranged in relation to the digging-apparatus, as and for the purpose set forth.

3. The arm J, cross-head K, spades or picks L M, and keys R, arranged in the manner and for the purpose substantially as specified.

4. The construction and arrangement of the spades and picks when combined with the compound crank, and operated in the manner and for the purpose substantially as set forth.

N. A. GRAY.
